CLAIM

The ornamental design for a medical imaging device as shown and described.

DESCRIPTION

FIG. 1 is a top-front-left perspective view of a medical imaging device according to the claimed design.

FIG. 2 is a bottom-front-right perspective view of the medical imaging device.

FIG. 3 is a front view of the medical imaging device.

FIG. 4 is a rear view of the medical imaging device.

FIG. 5 is a right side view of the medical imaging device.

FIG. 6 is a left side view of the medical imaging device.

FIG. 7 is a top view of the medical imaging device.

FIG. 8 is a bottom view of the medical imaging device.

FIG. 9 is a right side view of the wall stand of the medical imaging device; and,

FIG. 10 is a left side view of the table and tube stand of the medical imaging device.

(Continued)

The broken lines in the drawings illustrate portions of the medical imaging device that form no part of the claimed design.
